SHOE SUPPORTING JACK

Ralph C. Simmons, deceased, late of Beverly, Mass., by Elizabeth D. Simmons, executrix, Beverly, Mass., assignor to United Shoe Machinery Corporation, Paterson, N. J., a corporation of New Jersey

Application March 31, 1933, Serial No. 663,746

25 Claims. (Cl. 12—17)

The present invention relates to shoe supporting jacks and particularly to improvements in devices for positioning a templet for guiding a shoe engaging tool about a jacked shoe, as in the machine illustrated and described in the U. S. Patent to Alfred R. Morrill, No. 1,897,526 dated February 14, 1933.

In the machine of the Morrill patent, the lasted shoe is supported upon a toe rest and a heel support, and a templet is secured to the bottom of the shoe by a clamp member pressing the templet downwardly against the shoe. The templet is located in position on the surface of the shoe at the toe end by the conical end of a pin carried by the templet, engaging an indentation in the bottom of the shoe, and at the heel end by the head of a pin passing through the sole of the shoe and into the last which supports the shoe. The heel end of the templet is slotted and surrounds the head of the pin, thus preventing lateral movement. The last employed with the templet in making the shoe is provided with a positioning hole in its bottom surface to locate the templet properly when the pin is inserted. The last must therefore be specially drilled for use in this type of machine.

An object of the present invention is to provide a novel and improved jack for supporting a templet in predetermined position on the bottom surface of a shoe carried by a last of ordinary commercial type in which no special templet positioning pin hole has been formed.

Another object of the invention is to provide a novel and improved automatically adjustable gaging device for positioning a templet on the bottom surface of a shoe, and for retaining the templet in the desired position throughout the operation or operations for which the templet is employed.

With these objects in view, a feature of the present invention contemplates the provision in a jack having a heel support and toe rest on which a lasted shoe may be secured and means for clamping a templet against the sole of the shoe, of a gaging device cooperating with the sides of the shoe upper for positioning the templet on the shoe sole. As hereinafter described, the gaging device for positioning the templet is provided with a member engaging the slotted end of the templet at the heel end of the shoe.

The jack of the Morrill machine is provided with a clamp mounted on an arm pivoted on the jack to permit the clamp to swing towards and from operative position, so that the shoe may

readily be removed from the jack at the end of the operation on the shoe.

While the gaging devices of the present invention may be considered broadly to include any suitable means for positioning the shoe by engagement with a templet on the shoe and by contact with the sides of the shoe upper, and may be associated with the jack in any suitable manner, a further feature of the invention contemplates mounting the gaging device on the arm which supports the clamp, so that when the clamp is moved towards operative position, the gaging device will automatically be moved into cooperation with the shoe. To facilitate proper positioning of the gaging device in accordance with this feature of the invention, a guide is provided for the clamp arm on the jack, arranged to frictionally engage the clamp arm and hold it in the position to which it is moved before the clamp is actuated. In order to employ the gaging device with different sizes of shoes and to prevent the operation of the clamp by reason of its resilient connection with the jack from affecting the gaging device, the gaging device is pivoted to the clamp arm for movement towards and from the bottom surface of the shoe, and the templet engaging member of the gaging device is caused to move into contact with the templet when the clamp is brought into operating position by means acted on by the heel end of the shoe. The gaging device is also so mounted on the clamp supporting arm, that it may move bodily parallel to the plane of the shoe sole to a position determined by the gage members.

A further feature of the invention contemplates the provision in a gaging device for positioning a templet on the bottom surface of the shoe, having gages connected together to move in opposite directions laterally of the shoe, and a templet centering gage, of means for automatically preventing movement of the lateral gages after being brought to gaging position. The means for preventing movement of the gages may consist of any suitable arrangement for locking the gages in place, and in the form shown, mechanism is provided for frictionally preventing movement of the gages as a result of thrust on the templet centering gage.

Other features of the invention consist in the novel constructions, combinations and arrangements of parts hereinabove described and claimed, the advantages of which will be understood by those skilled in the art from the following description.

vention in its preferred form, Fig. 1 is a view in front elevation of a jack showing a templet clamped to the shoe outsole; Fig. 2 is a plan view of the jack illustrated in Fig. 1; Fig. 3 is a view in side elevation looking from the left of Fig. 1, of a lower portion of the jack; Fig. 4 is a view in front elevation illustrating the jack in open position, the position to which the clamp is moved in order to disengage the shoe being indicated 10 in dot-and-dash lines; Fig. 5 is a plan view partly in section of a portion of the gaging device of the present invention, with the shoe and templet indicated in cooperating position, taken along the line 5—5 of Fig. 9; Fig. 6 is a plan view partly 15 in section of portions of the same device in the position assumed when the shoe is removed, taken along the line 6—6 of Fig. 10; Fig. 7 is a vertical sectional view of the positioning device taken along the line 7—7 of Fig. 5; Fig. 8 is another sectional view taken along the line 8—8 of Fig. 5; Fig. 9 is a view in elevation and partly in section taken along the line 9—9 of Fig. 5; and Fig. 10 is a similar view taken along the line 10—10 of Fig. 6.

25 The jack illustrated in the drawings is provided with a toe rest 2 formed integrally with a supporting post 4, and a heel support 6 pivotally mounted at 8 to the supporting post, and movable towards and from the toe rest 2 for 30 securing an inverted lasted shoe, indicated at 10, to the jack. The heel support is provided with a last pin 9 arranged to engage the pin hole in the last and to be operated to lock the shoe in place by a handle lever 12 on the jack. 35 To release the shoe, a releasing finger 14 is located on the toe rest just below the shoe. Since the specific construction and operation of the shoe supporting mechanism of the jack is immaterial so far as the present invention is concerned, further description and illustration has 40 been omitted from this application.

As in the machine of the Morrill patent referred to, the jack may be mounted to tip and turn and be moved to feed the shoe with respect to any of a number of operating devices such as an edge trimming cutter, indicated diagrammatically in Fig. 2 at 16. The contour of the sole on the shoe is shaped by the cutter 16, and the shoe is guided by the templet 18 on the bottom surface of the shoe, the shoe being forced towards the cutter until stopped by a guide indicated diagrammatically in Fig. 2 at 19, fixed to the machine to cooperate with the templet 18. The templet is secured against the shoe by a 45 clamp mounted on the upper end of a supporting arm 22 and actuated by a cam lever 24 on the arm. The arm 22 is forked at its lower end and is pivotally mounted on the jack at 26 to swing towards and from a position in which the clamp 20 may cooperate with the templet to 50 secure it in place.

To locate the toe portion of the templet on the bottom of the shoe, the templet is provided with a pointed set screw or pin 28 projecting from the sole engaging surface of the templet into an indentation formed at a predetermined 55 location in the surface of a sole.

In accordance with a feature of the present invention, the heel end of the templet is located and held in predetermined position on the shoe by gaging means cooperating with the sides of the shoe upper and with the inner surfaces of a slot 30 formed substantially parallel to the sides of the shoe at the heel end of the templet and to the length of the templet. The gaging means is

supported by a frame composed of a pair of horizontal cross bars 32 and 34 (see Fig. 7) secured together by screws 36. The gage frame is connected to the supporting arm 22 for the templet clamp 20 by parallel links 38, a block 40, and a pivot shaft 42 passing through and secured to a lug of the arm 22, and journaled at its ends in upstanding lugs on the block 40. When the clamp 20 is moved into operative position, the gaging means moves with the arm 22 into contact with the shoe.

To locate the templet in a central position on the shoe, the gage member which cooperates with the slot 30 of the templet comprises an arm 43 extending from the gage frame over the heel end 15 of the shoe. The position of the arm 43 relative to the shoe is determined by the gage members which act on the sides of the shoe to center the arm 43 on the heel.

The members of the gage which cooperate with the sides of the shoe upper comprise laterally movable gage arms or levers 44 pivotally mounted for support on sleeves 46 surrounding the screws 36 in the frame of the gaging device. The gage levers 44 are connected together to move towards and from each other simultaneously by links 48 pivotally connected between arms of the levers 44 and to either edge of a block 50. The block 50 is slidably mounted on a guide member 52 fixed by screws 53 to the lower cross bar 34 of the gage frame, so that the block 50 is caused to move in a straight line on the frame producing equal movements of the levers 44. The arms of the gage levers 44 which cooperate with the sides of the shoe are, when no shoe is between them, moved towards each other by a spring 54 stretched between a pin on the block 40 and a small hook mounted in the block 50, causing the block to be yieldingly drawn towards the clamp supporting arm 22.

To insure that the side gage arms 44 will always contact with both sides of the shoe upper, the gage is permitted to move bodily, laterally of the shoe on the clamp supporting arm 22. The connection provided by the parallel links 38 which pivot about the sleeves 46 on the screws 36 and about sleeves 55 and screws 56 in the block 40, permits the gage to be maintained in the same angular relation to the shoe when these links swing on their pivots, and the spring 54 being shorter than the links serves to maintain the gage as a whole in an intermediate position relative to the clamp supporting arm 22 when not engaging the shoe.

The gage is also movable on the clamp supporting arm towards and from the bottom surface of the shoe about the shaft 42 which passes loosely into the ends of the block 40. When the gage is disconnected from the shoe, it is rocked about the shaft 42 to move the gage upwardly away 60 from the templet on the shoe by a spring 57 compressed between one end of a passage in the arm 22 and a projection on the block 40 which rotates about the shaft 42 and forms a part of the mounting for the gage. When the gage is moved with 65 the arm 22 towards the heel of the shoe, the lateral gage levers 44 contact with either side of the upper at the heel end of the shoe. To cause the gage to be moved downwardly towards the shoe bottom against the spring 57, the gage 70 is provided with a plate 58 against which the heel end of the shoe bears after the levers 44 engage the sides of the upper. When the gage is moved with the arm 22 away from the shoe, the upward movement of the gage by the spring 57 is 75

limited by a set screw 59 mounted in a lug on the arm 22 in a position to engage a projection on the block 40.

To cause the clamp 20 to act more uniformly for different sizes of shoes than in the machine described in the Morrill patent, the clamp arm 22 is resiliently connected to the jack. The pivot 26 for the arm 22 comprises a pair of studs threaded into each part, respectively, of the 10 forked end of the arm and engaged at their inner ends in recesses in a two part block 60 surrounding the supporting post 4 for the jack. The parts of the block 60 are secured together by screws 61 to slide vertically on the post 4 and the block is 15 yieldingly maintained in lowered position on the supporting post by a pair of springs 62 carried by the block and engaged at their upper ends by a split collar 64 fixed to the supporting post 4. To limit the downward movement of the pivot supporting block 60, a second split collar 66 is secured to the supporting post beneath the block 60. When the clamp 20 is actuated against the 20 templet 18 on the shoe, the arm 22 is raised slightly with the block 60 to compress the springs 25 62.

When the shoe is released from the jack, the heel support 6 is moved away from the toe rest 2 as shown in Fig. 4. The toe of the shoe is lowered relatively to the clamp 20 so that the clamp releases the templet 18. To limit the movement of the arm 22 after the shoe is released, the lower part of the arm cooperates with an arcuate guide 68 connected at one end by a pivot 70 to the lower end of the heel support 6 and surrounded by the 30 forked lower end of the clamp arm 22. The free end of the guide 68 is hooked and is engaged by a pin 71 passing through the arm 22, when the arm is in its lowermost position. To assist in positioning the gage and clamp, the guide 68 is forced into frictional engagement with the pin 71 by a spring pressed plunger 72 slidably mounted in the clamp arm and arranged to engage the upper edge of the guide 68.

In order to permit the position of the templet to be adjusted for different shoe styles or rights or lefts of the same style, the templet centering gage arm 43 is formed at its forward end with a spherical surface of a diameter to fit closely within the slotted end of the templet. The arm 43 45 may then be shifted at an angle to the length of the templet while still retaining a close fit with the slot 30. The templet gage arm is releasably clamped by a screw 74 to the upper end of a shaft 76 mounted in the upper frame cross bar 32, the lower end of the shaft being connected to a guide block 78. By loosening the screw 74 the position of the templet relative to the center line of the shoe when the lateral gages contact with the upper may be regulated.

The gage arm is held against rotation with the shaft 76 by the block 50 in which is formed a slot 80 closely fitting beveled gages of the guide block 78. To prevent lost motion between the guide block 78 and the slot while permitting the block to slide freely in the block 50, one end of the guide block 78 is slotted and a screw 82 having a conical head is threaded into an opening between portions of the block at opposite sides of the slot. Rotation of the screw 82 tends to separate the 55 portions of the block and to cause the beveled edges to fit more exactly with the sides of the slot 80.

During the operation of a machine in which the jack is supported, the edge trimming or other operating tool is guided about the shoe by

the engagement of the fixed guide 19 (see Fig. 2) along the edges of the templet. When the heel end of the shoe is reached, the thrust on the templet produced by the guide 19 is imparted to the templet centering gage arm 43 and to the guide block 78 connected with the gage arm, causing the guide block 78 to rotate slightly and thus be forced into frictional engagement with the block 50 and hold the block from movement. The block 50 is also rotated slightly and is thus 10 also held from movement with the guide block 78 by the guide member 52 on the cross bar 34. Due to the frictional engagement of the blocks 78, 50 and the guide member 52, the gage levers 44 are locked against separation from the shoe 15 so that the thrust of the fixed guide 19 on the templet is automatically resisted by the gage. The greater the pressure on the templet, the greater will be the frictional effect produced in the gage so that there is no possibility of shifting the templet relatively to the shoe while in use. At the end of the operation, the jack being moved away from the guide 19 in the same manner as in the machine of the Morrill patent, the locking means on the gage becomes inoperative 20 and the gage may readily be disconnected from the shoe.

The nature and scope of the invention having been indicated, and a construction embodying the invention having been specifically described, 30 what is claimed is:—

1. A jack for supporting a shoe and a guiding templet associated therewith having, in combination, means for supporting a shoe, means for securing the templet against the sole of a shoe 35 mounted on the supporting means, and a templet positioning device comprising members movable into engagement with the templet and the sides of the shoe while the shoe is supported in the jack.

2. A jack for supporting a shoe and a guiding templet associated therewith having, in combination, means for supporting a shoe, means for securing the templet against the sole of a shoe 40 mounted on the supporting means, and a templet positioning device comprising interconnected 45 members engaging the sides of the shoe and surfaces on the templet parallel with the length of the templet.

3. A jack for supporting a shoe and a guiding templet associated therewith having, in combination, means for supporting a shoe, means for securing the templet against the bottom surface 50 of the shoe mounted on the supporting means, and a templet positioning device comprising interconnected members engaging the sides of the shoe and a slot in the heel end of the templet.

4. A jack for supporting a shoe and a guiding templet associated therewith having, in combination, means for supporting a shoe, a clamp for 55 securing a templet against the bottom surface of a shoe mounted on the supporting means, a clamp supporting arm pivotally mounted on the jack to permit the clamp to be swung towards and away from engagement with the templet, and a templet positioning device supported on the clamp arm arranged to engage the templet and position the templet with relation to the shoe.

5. A jack for supporting a shoe and a guiding templet associated therewith having, in combination, means for supporting a shoe, a clamp for 60 securing a templet against the bottom surface of a shoe mounted on the shoe supporting means, a clamp supporting arm pivotally mounted on the jack to permit the clamp to be swung towards 65 and away from engagement with the templet, and a templet positioning device supported on the clamp arm arranged to engage the templet and position the templet with relation to the shoe.

75

- and away from engagement with the templet, and a templet positioning device on the clamp arm arranged to engage the templet and the shoe when the clamp is swung towards the templet.

6. A jack for supporting a shoe and a guiding templet associated therewith having, in combination, means for supporting a shoe, a clamp for securing a templet against the bottom surface of a shoe mounted on the shoe supporting means, a clamp supporting arm pivotally mounted on the jack to permit the clamp to be swung towards and away from engagement with the templet, a templet positioning device on the clamp arm, a guide for the clamp arm, and means acting on the guide for frictionally retaining the clamp arm in a position to which it is moved.

7. A jack for supporting a shoe and a guiding templet associated therewith having, in combination, means for supporting a shoe, a clamp for securing a templet against the bottom surface of a shoe mounted on the shoe supporting means, a clamp supporting arm pivotally mounted on the jack to permit the clamp to be swung towards and away from engagement with the templet, and a templet positioning device pivoted on the clamp arm for movement towards and from the bottom surface of the shoe.

8. A jack for supporting a shoe and a guiding templet associated therewith having, in combination, means for supporting a shoe, a clamp for securing a templet against the bottom surface of a shoe mounted on the shoe supporting means, a clamp supporting arm pivotally mounted on the jack to permit the clamp to be swung towards and away from engagement with the templet, a templet positioning device pivoted on the clamp arm for movement towards and away from the bottom surface at the heel end of the shoe, and means connected to the positioning device and arranged to be engaged by the heel end of the shoe to cause the positioning device to be retained in proximity with the shoe bottom when the clamp is brought into operating position.

9. A jack for supporting a shoe and a guiding templet associated therewith having, in combination, means for supporting a shoe, a clamp for securing a templet against the bottom surface of a shoe mounted on the shoe supporting means, a clamp supporting arm pivotally mounted on the jack to permit the clamp to be swung towards and away from engagement with the templet, a templet positioning device pivoted on the clamp arm for movement towards and away from the bottom surface at the heel end of the shoe, means connected to the positioning device and arranged to be engaged by the heel end of the shoe to cause the positioning device to be retained in proximity with the shoe bottom when the clamp is brought into operating position, and a spring for rocking the templet positioning device about its pivot on the clamp arm to move it away from the shoe bottom as the clamp is moved away from operating position.

10. A jack for supporting a shoe and a guiding templet associated therewith having, in combination, means for supporting a shoe, a clamp for securing a templet against the bottom surface of a shoe mounted on the supporting means, a clamp supporting arm pivotally mounted on the jack to permit the clamp to be swung towards and away from engagement with the templet, a templet positioning device pivoted on the clamp arm for movement towards and away from the bottom surface at the heel end of the shoe, means connected to the positioning device and arranged

5 to be engaged by the heel end of the shoe to cause the positioning device to be retained in proximity with the shoe bottom when the clamp is brought into operating position, and a mounting for the clamp arm on the jack arranged to yield when the clamp is actuated.

11. A jack for supporting a shoe and a guiding templet associated therewith having, in combination, means for supporting a shoe, a supporting arm on the jack movable towards and from the shoe, a templet positioning device, gages on the positioning device arranged to cooperate with the upper of the shoe and with the templet, and mounting means on the supporting arm for the positioning device to permit said device to move bodily to a position determined by the gages on the shoe upper.

12. A jack for supporting a shoe and a guiding templet associated therewith having, in combination, means for supporting a shoe, a supporting arm movable on the jack in a direction lengthwise of the shoe towards and from the heel end of the shoe, a templet positioning device, gages on the positioning device arranged to cooperate with sides of the upper of the shoe and with the templet on the shoe, and mounting means for the positioning device on the supporting arm to permit the gages which cooperate with the upper to move with the templet gage laterally while maintaining the relative lateral spacings of the gages.

13. A jack for supporting a shoe and a guiding templet associated therewith having, in combination, means for supporting a shoe, a supporting arm movable on the jack in a direction lengthwise of the shoe towards and from the heel of the shoe, a templet positioning device, gages on the positioning device arranged to cooperate with the sides of the upper at the heel of the shoe and with the templet on the shoe, mounting means for the positioning device on the arm to permit a gage of the positioning device cooperating with the templet to move towards and from the bottom surface of the heel end of the shoe and the gages of the positioning device which cooperate with the upper to move laterally with the templet gage while maintaining the relative spacings of the gages, and means connected to the positioning device and engaged by the heel end of the shoe as the supporting arm is being moved towards the shoe heel to cause the templet gage of the positioning device to be moved towards the bottom of the shoe after the side gages have moved against the upper.

14. A jack for supporting a shoe and a guiding templet associated therewith having, in combination, means for supporting a shoe, a supporting arm on the jack movable towards and from the shoe, a templet positioning device on the arm, gages on the positioning device arranged to cooperate with the upper at the heel end of the shoe, and resilient means arranged to cause said gages to yieldingly engage the sides of the upper when the positioning device is moved towards the shoe.

15. A jack for supporting a shoe and a guiding templet associated therewith having, in combination, means for supporting a shoe, a supporting arm on the jack movable lengthwise of the shoe towards and from the heel end of the shoe, a templet positioning device, gages on the positioning device arranged to cooperate with the upper at the heel end of the shoe, parallel links for connecting the positioning device to the supporting arm to permit the positioning device to be

5 moved transversely to the length of the shoe as the gages are brought into operating position, and a spring acting to move said gages together and to bring the positioning device to an intermediate position when disengaged from the shoe.

10 16. A jack for supporting a shoe and a guiding templet associated therewith having, in combination, means for supporting a shoe, a supporting arm pivoted on the jack to swing towards and from the shoe, a templet positioning device mounted on the arm, lateral gages on the positioning device connected to each other to move in opposite directions, a templet centering gage on the positioning device to move with the positioning device when both lateral gages contact with the shoe, and resilient means for causing the lateral gages to engage the shoe upper when the supporting arm is swung towards the shoe.

15 17. A jack for supporting a shoe and a guiding templet associated therewith having, in combination, means for supporting a shoe, means for securing a templet against the bottom surface of a jacked shoe, a supporting arm on the jack movable towards and from the shoe, a templet positioning device mounted on the arm, lateral gages on the positioning device connected to each other to move in opposite directions, a templet centering gage on the positioning device to move with the positioning device when both lateral gages contact with the shoe, a spring for causing the lateral gages to engage the shoe upper at the sides of the shoe when the arm is moved towards the shoe, and means for preventing movement of the lateral gages on the positioning device relatively to each other when force is applied to the templet centering gage.

20 18. A gaging device for positioning a guiding templet on a lasted shoe having, in combination, a frame, lateral gages mounted on the frame and connected together for simultaneous movement towards and from the sides of the shoe, a templet centering gage on the frame extending to a position intermediate the lateral gages, a spring for causing the lateral gages to engage the shoe upper at the sides of the shoe, and means on the positioning device for locking the lateral gages in place when force is applied to the templet centering gage.

25 19. A gaging device for positioning a guiding templet on a lasted shoe having, in combination, a frame, lateral gages mounted on the frame and connected together for simultaneous movement towards and from the sides of the shoe, a templet centering gage movable on the frame, a block connected to the lateral gages, a sliding mounting member for the block on the frame, and a connection between the block and the templet centering gage for causing the block to be thrust against the mounting member and frictionally prevent relative movements of the lateral gages when force is applied to the templet centering gage.

30 20. A gaging device for positioning a guiding templet on a lasted shoe having, in combination, a frame, lateral gages mounted on the frame and connected together for simultaneous movement towards and from the sides of the shoe, a templet centering gage arm pivoted on the frame for

movement between the lateral gages, a guide piece mounted to turn with the centering gage arm, and a block connected with the lateral gages and slidably connected to the guide piece to cause the guide piece to be thrust against the block and frictionally prevent relative movement of the lateral gages when force is applied to the centering gage arm.

10 21. A gaging device for positioning a guiding templet on a lasted shoe having, in combination, a frame, lateral gages mounted on the frame and connected together for simultaneous movement towards and from the sides of the shoe, a templet centering gage arm pivoted on the frame for movement between the lateral gages, a guide 15 piece mounted to rotate with the centering gage arm, a block connected to the lateral gages and slidably connected to the guide piece, a sliding mounting member for the block on the frame arranged to be thrust against the block when force 20 is applied to the guide piece through the templet centering gage and to prevent relative movement of the lateral gages thereby.

25 22. A gaging device for positioning a guiding templet on a lasted shoe having, in combination, a frame, lateral gages mounted on the frame and connected together for simultaneous movement towards and from the sides of the shoe, and a templet centering gage on the frame extending to a position intermediate the lateral gages. 30

23. A gaging device for positioning a guiding templet on a lasted shoe having, in combination, a frame, lateral gages mounted on the frame and connected together for simultaneous movement towards and from the sides of the shoe, a templet 35 centering gage on the frame extending to a position intermediate the lateral gages, and a spring for causing the lateral gages to engage the shoe upper at the sides of the shoe.

30 24. A gaging device for positioning a guiding templet on a lasted shoe having, in combination, a frame, lateral gages mounted on the frame and connected together for simultaneous movement towards and from the sides of the shoe, a templet centering gage extending to a position intermediate 45 the lateral gages, and means for adjustably securing the centering gage arm nearer to one or the other of the lateral gages when used with differently shaped shoes.

40 25. A gaging device for positioning a guiding templet on a lasted shoe having, in combination, a frame, lateral gages mounted on the frame, and connected together for simultaneous movement towards and from the sides of the shoe, a shaft secured within the frame, a templet centering gage arm formed with curved surfaces at 50 its free end adapted to fit within the slotted end of a templet and rotatably mounted on the shaft to position the templet in different positions relative to the center line of the shoe when the lateral gages are in contact with the sides of the shoe, and clamping means for adjustably securing the centering gage in fixed angular position on the shaft. 55

60 65 ELIZABETH D. SIMMONS,
*Executrix of the Will of Ralph C. Simmons,
Deceased.*
